(57) **CLAIM**

The ornamental design for a stove front, as shown and described.

DESCRIPTION

FIG. 1 is a perspective view of a stove front showing our ornamental design;

FIG. 2 is a front view of the stove front shown in FIG. 1; FIG. 3 is a top view of the stove front shown in FIG. 1; FIG. 4 is a left side view of the stove front shown in FIG. 1; and,

FIG. 5 is a right side view of the stove front shown in FIG. 1.

The broken line showing of environment in the drawings is for illustrative purposes only and forms no part of the claimed design.
